(57) **CLAIM**

The ornamental design for a lid latch, as shown and described.

DESCRIPTION

FIG. 1 shows a perspective view of a lid latch;

FIG. 2 shows a right side of the lid latch;

FIG. 3 shows a left side of the lid latch;

FIG. 4 shows a rear view of the lid latch;

FIG. 5 shows a front view of the lid latch;

FIG. 6 shows a top plan view of the lid latch; and,

FIG. 7 shows a bottom plan view of the lid latch.

The shade lines in the Figures show contour and not surface ornamentation.
